DEAD-END-WIRE CONNECTION

Application filed September 16, 1926. Serial No. 135,796.

This invention relates to connectors and especially a connector such as is required to anchor the end of an aerial wire.

A principal object of this invention is to produce a dead end connection for a wire line which will be simple to manufacture, inexpensive to manufacture, easy and inexpensive to install and efficient in use.

Other objects and advantages will appear as the description of the particular physical embodiment selected to illustrate the invention progresses, and the novel features of the invention will be particularly pointed out in the appended claim.

In describing the invention in detail, and the particular physical embodiment selected to illustrate the invention, reference is had to the accompanying drawing, wherein we have illustrated a particular preferred physical embodiment of the invention, and wherein like characters of reference designate corresponding parts throughout the several views, and in which:

Figure 1, is a side elevational view of our dead end connection, including a support to which it is attached, and the wire held by it; Fig. 2, is a cross sectional view on the plane indicated by the line II-II of Fig. 1, viewed in the direction of the arrows at the ends of the line.

In the drawings the numeral 1 indicates a fragment of the well-known cross-arm. Through an orifice in the cross arm 1, extends the member 2, which in the form shown is a cylindrical metal member, screw threaded on one end and made integral, on the other end, with an elongated annulus 3. A nut 4, is threaded onto the end of the member 2, and so serves to hold the member 2 in position in the cross arm. The usual washers 5 and 6, are interposed, as shown, as is usual, so that the wood of the cross arm is not injured.

The annulus is in form elongated, the body being preferably made of round metal, preferably iron. The end portions of the annulus

are dissimilar. One end is struck from a center, as 7, whereas the other end is struck from a center, as 8, to two being merged by the line as 9. This construction provides a space about the center 7, through which the annulus 10 made of insulating material, may readily pass transversely to the annulus 3. The annulus 10 is formed with a peripheral groove 11, so that when the annulus 10 is positioned in the space of which 7 is the center, and then pushed toward the other end portion of the annulus 3, the groove 11, contacts with the body of the annulus 3, so that when the annulus 10 is in the position as shown in Fig. 1, it cannot then be moved transversely to the annulus 3. The position of the annulus 10 as shown in Fig. 1, is the position which the annulus 10 would take and remain in when pulling force is applied to the wire 16, which dead ends at the annulus 10, by being looped through the orifice 12 in the annulus 10, and then fastened to itself by any suitable means as by a clamp 13.

Applicants prefer to make the annulus 10 somewhat elongated as shown in side elevational view in Fig. 1, so that better bearing of the body of annulus 3 in the peripheral groove 11, is obtained.

Although we have particularly described the construction of one physical embodiment of our invention, and explained the operation and principle thereof, nevertheless, we desire to have it understood that the form selected is illustrative, but does not exhaust the possible physical embodiments of the idea of means underlying our invention.

What we claim is new and desire to secure by Letters Patent of the United States is:

A dead end construction for a wire line, comprising an elongated annulus of substantially circular cross-section and having opposite end portions constructed with openings formed upon different radii, the opening of the inner end portion being larger than the opening of the outer portion, a second annulus

formed with a peripheral groove and of such size that it will pass freely through the larger opening but will be held within the smaller opening with the inner wall of the opening fitting snugly within said peripheral groove, and an integral stem projecting outwardly from the enlarged end of the elongated annulus in the direction of the longitudinal axis thereof, said stem being threaded at its outer end.

19 WILLIAM H. B. LAVARACK.
RAY PATTERSON.
